US00D732822S

(12) **United States Design Patent**
Griffin et al.

(10) **Patent No.:** **US D732,822 S**
(45) **Date of Patent:** **** Jun. 30, 2015**

(54) **CHILD RESISTANT STORAGE DEVICE**

(71) Applicants: **Jeremy Griffin**, Northridge, CA (US);
Jacob Griffin, Lancaster, CA (US);
David Weidenbach, Costa Mesa, CA (US)

(72) Inventors: **Jeremy Griffin**, Northridge, CA (US);
Jacob Griffin, Lancaster, CA (US);
David Weidenbach, Costa Mesa, CA (US)

(**) Term: **14 Years**

(21) Appl. No.: **29/521,003**

(22) Filed: **Mar. 19, 2015**

(51) LOC (10) Cl. **03-01**

(52) U.S. Cl.

USPC **D3/273**

(58) **Field of Classification Search**

(57) **CLAIM**

The ornamental design for a child resistant storage device, as shown and described.

DESCRIPTION

FIG. 1 is a perspective view embodying the inventive design; FIG. 2 is an exploded perspective view thereof showing the body at the bottom and the cap at the top; FIG. 3 is a side view of the device thereof; FIG. 4 is a top view of the device thereof; FIG. 5 is a bottom view of the device thereof; FIG. 6 is a perspective view of the cap thereof; FIG. 7 is a side view of the cap thereof; FIG. 8 is a top view of the cap thereof; FIG. 9 is a bottom view of the cap thereof; FIG. 10 is a perspective view of the body thereof; FIG. 11 is a front view of the body thereof; FIG. 12 is a side view of the body thereof; FIG. 13 is a top view of the body thereof; and, FIG. 14 is a bottom view of the body thereof. The broken line showing is for the purpose of illustrating portions of the article or environmental structure and forms no part of the claimed design.

1 Claim, 7 Drawing Sheets
